UNITED STATES PATENT OFFICE.

GEORGE Q. HAMMELL, OF DELANCO, NEW JERSEY.

REFRIGERATOR.

982,056.

Specification of Letters Patent. Patented Jan. 17, 1911.

Application filed December 22, 1908. Serial No. 468,809.

To all whom it may concern:

Be it known that I, GEORGE Q. HAMMELL, a citizen of the United States, residing at Delanco, in the county of Burlington, State 5 of New Jersey, have invented certain new and useful Improvements in Refrigerators; and I do hereby declare the following to be a full, clear, and exact description of the invention, such as will enable others skilled in 10 the art to which it appertains to make and use the same.

The present invention has reference to refrigerators, and more particularly to that type of refrigerator which is arranged to be 15 cooled by being lowered into a well or cistern and to be raised into position within a casing resting upon the floor above the well when access to its contents is desired. The well-cooled refrigerators now manufactured are, 20 however, objectionable in that their casings are bottomless, or in other words, open at their lower ends, by reason of which construction, they are seldom used, since there 25 is a serious danger that any small children playing upon the floor might open the casing door and fall into the well shaft.

It is the object of my invention, therefore, to overcome this defect by providing the casing with a pair of doors arranged to automatically 30 close the lower end of the casing and in consequence, the entrance to the shaft when the refrigerator is in its normal or lowered position, and to be automatically opened by the refrigerator as the latter enters 35 the casing.

The preferred embodiment of the invention is illustrated in the accompanying drawings, in which corresponding parts are designated by the same reference numerals 40 throughout the several views.

Of the said drawings, Figure 1 is a perspective view partly in section of the complete invention, the refrigerator proper being shown in lowered position. Fig. 2 is a vertical 45 sectional view showing the refrigerator in raised position within the casing. Fig. 3 is an enlarged detail view of the hand wheel showing the dog carried thereby. Fig. 4 is a detail view of the stop carried by the cable. Fig. 5 is a detail vertical section taken on the line 5—5 of Fig. 1, illustrating one of the supporting ribs upon which the doors rest in closed position. Fig. 6 is an enlarged 50 transverse section taken on the line 6—6 of Fig. 1.

Referring more particularly to the draw-

ings, 1 designates, generally, the refrigerator proper, 2 the casing, and 3 the floor above the well shaft 4, the casing resting upon the floor and being secured thereto in any preferred manner. 60

The refrigerator 1, whose dimensions are such that it can fit within the interior of the casing when in raised position is arranged to be lowered through the lower end 65 of the casing and through an opening 5 formed in the floor, into the shaft of the well, the top of the refrigerator having set thereinto a hook 6 to which one end of a cable 7 is fastened. The cable is then led upwardly 70 through a hole 8 in the top of the casing and trained over the grooved periphery of a pulley 9 rotatably mounted upon a lateral pin set into the upper portion of a standard 10 mounted upon the casing top. After passing 75 over the pulley, the cable is led downwardly back of the casing through a hole (not shown) in the floor into the well shaft, the end of this portion of the cable having a weight 11 secured thereto, for the purpose 80 of retarding the descent of the refrigerator, the extent of such movement being limited by means of a stop 12, secured to the cable and arranged to engage the floor.

The pulley, which is rotated by means of 85 its handle 13, is provided with a ratchet wheel 14, arranged to be engaged by a dog 25 pivoted to the upper end of the standard.

The lower end or bottom of the casing is closed, when the refrigerator is in its normal 90 or lowered position, by means of a pair of interiorly-located doors 15. These doors are hinged at their inner longitudinal edges to the sides of the casing, and extend toward each other when closed, as shown in Fig. 1, in which 95 position their outer longitudinal edges are in mutual contact and their front ends rest upon ribs 16 secured to the inner face of a horizontal rail 17 secured at its ends to the lower front corners of the casing sides. The 100 outer longitudinal edges of the doors are formed centrally with mating recesses 18 which unite in forming an opening for the cable when said doors are closed. These doors are arranged to open upwardly and 105 to swing away from each other into vertical position against the sides of the casing during the entrance of the refrigerator into the latter, such movement being effected by means of a pair of lugs 19 positioned upon 110 the refrigerator top, the lugs being in the form of alining metal straps secured at their

outer ends to said top and having their inner ends inclined upwardly and inwardly toward each other.

The refrigerator is guided directly into the casing during its upward movement by means of a narrow vertical board 20 which is secured to the inner face of the back wall of the casing and has its lower portion projecting into the well shaft, said guide board fitting slidably between a pair of spaced vertical cleats 21 secured to the outer face of the back wall of the refrigerator, the longitudinal edges of the guide boards and the inner longitudinal edges of the cleats being beveled, to hold the board against disengagement from the latter.

The interior of the refrigerator is divided into separate compartments by means of shelves 22, the compartments being closed by a door 23 hinged to the front edge of one of the side walls. The casing 2 is provided with a similarly located door 24.

From the foregoing, it will be apparent that the refrigerator, which is presumed to be in the position shown in Fig. 1, may be raised into the interior of the casing by merely rotating the pulley 9 in the proper direction, the engagement of the dog 14 with the ratchet wheel holding the refrigerator in such position. During the ascent of the refrigerator, the curved upper ends of the lugs 19 will be brought into contact with the under faces of the doors 16, causing the latter to swing upwardly away from each other or toward the sides of the casing, as the refrigerator continues its upward movement, the upper faces of the doors being virtually parallel with the inner faces of the sides when the limit of such movement is reached. The said lugs 19 come in contact with the top of the casing and coact therewith to arrest the ascent of the refrigerator and dispose it with the side door 23 thereof directly opposite the door 24 of the casing. The doors 24 and 23 may then be successively opened, thus affording access to the interior of the refrigerator. When the refrigerator is to be returned to its normal position within the well-shaft, it is necessary only to release the dog from engagement

with the ratchet wheel, whereupon the refrigerator will descend slowly of its own accord, the doors swinging inwardly toward each other, as the refrigerator leaves the interior of the casing, until their front ends rest upon the ribs 16. When the refrigerator has reached a certain point in its descent, the stop 12 will be brought into contact with the floor, thus terminating the descent. The provision of the beveled guide board 20, and its disposition between the beveled cleats 21, will prevent swinging movement of the refrigerator during its movements, and will also cause the refrigerator to move directly into the interior of the casing during its ascent. In addition to the stop 12, a second or safety stop 26 may be employed for terminating the descent of the refrigerator, this second stop being secured to the lower end of the guide board, as shown.

What is claimed is:—

The combination with a shaft and a casing located directly over the mouth thereof and having its lower end open and also having a cover, of a refrigerator, means to raise and lower the same through said open end of the casing into and out of the shaft, said casing having a side door and said refrigerator also having a side door on the same side as that of the casing, a pair of hatch doors hinged at their outer sides to opposite sides of the casing and located near the bottom thereof to close above the refrigerator when the latter is lowered and to open as the refrigerator ascends and enters the casing, and lugs on the upper side of the refrigerator for engaging the free ends of the hinged doors to open the same as the refrigerator ascends in the casing and to come in contact with the top of the casing and coact therewith to arrest the ascent of the refrigerator and dispose the side door thereof directly opposite that of the casing.

In testimony whereof, I affix my signature, in presence of two witnesses.

GEORGE Q. HAMMELL.
